(57) **CLAIM**

The ornamental design for a lamp, as shown and described.

DESCRIPTION

FIG. 1 is a first perspective view of the first embodiment of a lamp showing my new design;

FIG. 2 is a second perspective view of the first embodiment thereof;

FIG. 3 is a front view of the first embodiment thereof;
FIG. 5 is a left side view of the first embodiment thereof;
FIG. 6 is a right side view of the first embodiment thereof;
FIG. 7 is a top view of the first embodiment thereof;
FIG. 8 i is a bottom view of the first embodiment thereof;
FIG. 9 is a first perspective view of the second embodiment of a lamp showing my new design;

FIG. 10 i is a second perspective view of the second embodiment thereof;

FIG. 11 is a front view of the second embodiment thereof;
FIG. 12 is a back view of the second embodiment thereof;
FIG. 13 is a left side view of the second embodiment thereof;
FIG. 14 is a right side view of the second embodiment thereof;

FIG. 15 is a top view of the second embodiment thereof;
FIG. 16 is a bottom view of the second embodiment thereof;
FIG. 17 is an enlarged view of the selected portion 17 in FIG. 1;
